UNITED STATES PATENT OFFICE.

EDWIN FRANCIS CREAGER, OF LANCASTER, PENNSYLVANIA.

DESIGN FOR A BALL RETAINER AND SEPARATOR.

SPECIFICATION forming part of Design No. 30,181, dated February 14, 1899.

Application filed January 23, 1899. Serial No. 703,186. Term of patent 14 years.

To all whom it may concern:

Be it known that I, EDWIN FRANCIS CREAGER, a citizen of the United States, residing at Lancaster, in the county of Lancaster and State of Pennsylvania, have invented and produced a new and original Design for Ball Retainers and Separators; and I do hereby declare the following to be a full, clear, and exact description of the invention, such as will enable others skilled in the art to which it appertains to make and use the same.

The design herein illustrated is for a retainer or separator to hold and separate a number of balls—such, for example, as are commonly employed in bicycle-bearings.

The distinguishing feature of the design is the form—that of an oblate spheroid or cup-shaped annulus, with a central or axial space and an extension lip or flange. Each of a series of perforations around the spheroid has projecting tangs springing from one end of the tangential extensions in the perforations,

each tang having the portion between two perforations for a base.

In the drawings, Figure 1 is a top plan view with reference to Fig. 3; Fig. 2, a bottom plan view, and Fig. 3 a section on the line 3 3 of Fig. 2.

The spheroid is indicated by 1, the axial space by 2, the perforations about the spheroid or annulus by 3, the tangs by 4, and the extension or flange by 5.

In this illustration seven perforations are shown as an example.

What I claim is—

The design for a ball retainer and separator substantially as shown and described.

In testimony whereof I affix my signature in presence of two witnesses.

EDWIN FRANCIS CREAGER.
